ENCLOSURE

Spirou David, 1204 Meadowbrook Road,
North Merrick, N.Y. 11566

Filed Sept. 19, 1968, Ser. No. 13,609

Term of patent 14 years

Int. Cl. D7—99; D15—11
U.S. Cl. D49—35

FIG. 1 is a rear perspective view of a lid cover for a trash receptacle enclosure, showing my new design;

FIG. 2 is an end elevation thereof; and

FIG. 3 is a front elevation thereof, one lid shown in open position.

The characteristic of my design for trash receptacle enclosures resides in the configuration of the top lid members.

I claim:

The ornamental design for a lid cover for a trash receptacle enclosure, substantially as shown and described.
